Des. 195,490
Patented June 18, 1963

195,490

AMPHIBIOUS GROUND EFFECT MACHINE

Gabriel D. Boehler, Washington, D.C., and William F. Foshag, Westmorland Hills, Md.

Filed Feb. 24, 1961, Ser. No. 64,040

Term of patent 14 years

(Cl. D71—1)

FIG. 1 is a perspective view of an amphibious ground effect machine showing our new design.

FIG. 2 is a perspective view from the rear thereof.

FIG. 3 is a front elevational view thereof; and

FIG. 4 is a plan view of the bottom surface thereof.

The dominant features of our design reside in the portions shown in full lines.

We claim:

The ornamental design for an amphibious ground effect machine, as shown and described.
